(57) **CLAIM**

The ornamental design for an electronic device, as shown and described.

DESCRIPTION

FIG. 1 is a front plan view thereof;

FIG. 2 is a rear plan view thereof;

FIG. 3 is a right side view thereof;

FIG. 4 is a left side view thereof;

FIG. 5 is a top view thereof;

FIG. 6 is a bottom view thereof;

FIG. 7 is a front perspective view thereof; and,

FIG. 8 is a rear perspective view thereof.

The electronic device is not limited to the scale shown herein.

As indicated in the title, the article of manufacture to which the ornamental design has been applied is an electronic device. The electronic device may be a media player, e.g. music, video and/or game player; media storage device; a personal digital assistant; a communication device, e.g., cellular phone or smartphone; a novelty item, or toy.
